UNITED STATES PATENT OFFICE.

SANDY DUKES, OF BEAUMONT, TEXAS.

GRAIN-CAR.

1,371,877.

Specification of Letters Patent. Patented Mar. 15, 1921.

Application filed December 10, 1919. Serial No. 343,762.

To all whom it may concern:

Be it known that I, SANDY DUKES, a citizen of the United States, residing at Beaumont, in the county of Jefferson and State of Texas, have invented certain new and useful Improvements in Grain-Cars; and I do hereby declare the following to be a full, clear, and exact description of the invention, such as will enable others skilled in the art to which it appertains to make and use the same.

This invention relates to grain cars and the principal object of the invention is to provide an improved floor and bottom construction, the floor being provided with removable trap doors which may be put in place when the car is to be used for carrying ordinary freight and which will be removed and placed against side walls when the car is to be used for carrying grain.

Another object of the invention is to provide the bottom of the car with a construction which will cause the grain to feed out through side openings in the car and to further provide the bottom with drop doors which will be removably held in position and which may be released when it is desired to empty the car rapidly with the grain dropping beneath the car to a pit or hopper.

Another object of the invention is to so construct this car that if desired it may be emptied through the medium of a screw conveyer which will be inserted to one of the side openings of the car.

Another object of the invention is to so construct this improved car that freight cars already in use may be easily converted into the improved car construction.

Another object of the invention is to so construct this car that it will be strong and durable and at the same time comparatively simple in construction.

This invention is illustrated in the accompanying drawing, wherein:

Figure 1 is a side elevation of the improved grain car.

Fig. 2 is a bottom plan view of the car.

Fig. 3 is a horizontal section through the car.

Fig. 4 is a vertically extending longitudinal section through the car.

Fig. 5 is a transverse section through the car taken through the central portion thereof.

Fig. 6 is a detail showing one of the drop

doors and the fastening means for releasably retaining the same in a raised position.

This grain car is provided with a body having side walls 10, and walls 11, a flooring 12, and a roof 13 which roof is provided with the usual running board 14 and will be provided with inlet openings through which spouts may be passed thus permitting the car to be easily filled with grain. The side walls are provided with the usual doorways which will be closed by the sliding doors 16. It will thus be seen that the body portion of this freight car will have a conventional freight car construction. If desired the end walls may be provided with doorways through which bulky articles may be passed.

The flooring 12 will be braced by the usual longitudinally extending beams or sills 17 and cross beams 18 and the flooring will be cut out as shown in Fig. 3 thus providing a central opening 19 and end openings 20 which lead from the central opening 19 toward the ends of the car. Covers 21 and 22 are provided for the central and end openings and will be provided with lifting rings 23 so that these covers may be easily removed when desired. When in place these covers rest upon the beams 17 and 18 and therefore will be firmly supported when in place. When these covers are in place the car may be used as an ordinary freight car. When it is desired to use the car as a grain car the covers will be removed and placed along the sides of the car where they may be easily reached when the car is empty and it is desired to put them back in place.

A second or outer bottom 24 is provided for this freight car and will be preferably formed of heavy sheet metal which will be riveted or otherwise securely connected with the side plates 25 and will be fixed at an incline from the end portions of the car toward the central portion. The central portion of the bottom will be fixed at an incline from the center of the car toward the sides thereof and it will thus be seen that grain flowing through the openings in the flooring will be fed toward the central portion of the bottom and will then flow toward the sides of the car thus permitting the grain to feed out through the doorways 26 formed in the side plates 25 beneath the doorways 15 and normally closed by the doors 27. These doors 27 will only be open in case it is desired to feed grain through the door-

ways 26 into sacks or other small receptacles or when it is desired to insert a screw conveyer into the car through one of these doorways. The bottom will be provided 5 with a central opening 28 positioned beneath the central opening 19 of the flooring and with longitudinally extending end openings 29 which are positioned beneath the end openings 20. Drop doors 30 and 31 10 are provided for the openings 28 and 29 and are hingedly mounted so that they may be swung down to an open position. When closed the doors 30 and 31 are made secure by suitable latch or fastening means 32 as 15 indicated in the several views and more particularly in Fig. 6.

When this car is in use as an ordinary freight car the covers 21 and 22 will be put in place and a solid flooring will be provided. Ordinary freight can then be put 20 into the car through the side doors. When it is desired to load grain the covers 21 and 22 will be removed and set up against the side walls of the car thus leaving a clear 25 passage through the flooring to the sheet metal bottom of the car. The side doors will be closed and the grain will be fed into the car through the openings formed in the roof. When it is desired to unload the car 30 the drop doors may be opened and the grain passed through the bottom of the car into a hopper or pit. It is of course understood that all of these doors do not have to be open unless so desired. If it is desired to 35 remove the grain from the car through the medium of a screw conveyer one of the doors 26 may be opened and the screw conveyer inserted through the door. The grain will feed toward this conveyer due to the sloping 40 of the bottom. One of the doors may also be opened in case it is desired to fill sacks directly from the car and the grain will flow out of the side openings into the sack. There has therefore been provided a freight 45 car which can be easily converted into a grain car and which can be easily and quickly emptied and the flooring boards or covers put back in place thus returning the car to its original appearance as an ordinary freight car.

What is claimed is:—

1. A freight car comprising a body having a flooring provided with a central open-

ing and with end openings extending longitudinally of the flooring and leading from 55 the central opening, removable covers for the openings in the flooring, a bottom positioned in spaced relation beneath the flooring and having its end portions sloping downwardly toward the central portion 60 and having its central portion sloping from the center of the car toward the sides thereof, said bottom being provided with openings positioned beneath the central and end openings of the flooring, drop doors for closing 65 the openings of the bottom hingedly connected with the bottom and releasably held in an elevated position for closing the openings in the bottom, side plates positioned between the flooring and the sides of said 70 bottom and provided intermediate their length with outlet openings, the inclined intermediate portions of the bottom serving to direct grain toward the openings of the side plates, and removable closures for the 75 openings in the side plates.

2. A car body having an inclosed space below its bottom, the bottom of the inclosed space having its central portion oppositely inclined from a median longitudinal line 80 and provided with lower and outer discharge openings and having its end portions upwardly inclined toward the ends of the car and provided in its side portions with openings, and closures for the several 85 openings.

3. A car body having an inclosed space below its floor, the bottom of the inclosed space having its central portion oppositely inclined from a median longitudinal line 90 and provided with lower and outer discharge openings and having its end portions upwardly inclined toward the ends of the car and provided in its side portions with 95 openings, the floor of the car having openings corresponding with the openings in the bottom of the said inclosed space, and closures for the several openings in both of the said bottom and floor.

In testimony whereof I affix my signature in presence of two witnesses.

SANDY DUKES.
